US00D900043S

(12) **United States Design Patent** (10) **Patent No.:** **US D900,043 S**
Oneufer et al. (45) **Date of Patent:** **** Oct. 27, 2020**

(54) **SWITCH HANDLE FOR CIRCUIT BREAKERS**

(71) Applicant: **Eaton Intelligent Power Limited**,
Dublin (IE)

(72) Inventors: **Stephen William Oneufer**, Fayetteville, NC (US); **Edgar Yee**, Chapel Hill, NC (US); **Robert Allan Morris**, Fayetteville, NC (US); **Daniel Boyd Kroushl**, Clayton, NC (US)

(73) Assignee: **Eaton Intelligent Power Limited**,
Dublin (IE)

(**) Term: **15 Years**

(21) Appl. No.: **29/631,200**

(22) Filed: **Dec. 28, 2017**

Related U.S. Application Data

(60) Division of application No. 29/568,725, filed on Jun. 21, 2016, now Pat. No. Des. 809,468, which is a division of application No. 29/506,538, filed on Oct. 16, 2014, now Pat. No. Des. 762,593, which is a continuation-in-part of application No. 29/485,857, filed on Mar. 24, 2014, now Pat. No. Des. 751,516.

CLAIM

The ornamental design for a switch handle for circuit breakers, as shown and described.

DESCRIPTION

FIG. 1 is a front, side perspective view of a switch handle for circuit breakers showing our design;

FIG. 2 is rear, side perspective view thereof;

FIG. 3 is a top view thereof (the bottom view is disclaimed);

FIG. 4 is a side view thereof;

FIG. 5 is a side view opposite that shown in FIG. 4;

FIG. 6 is a rear view taken at 90 degrees from the view shown in FIG. 5; and,

FIG. 7 is a front view opposite that shown in FIG. 6.

The broken lines shown herein are for illustrative purposes only and form no part of the claimed design.

1 Claim, 3 Drawing Sheets
